UNITED STATES PATENT OFFICE

2,475,324

THREAD CUTTER FOR THIMBLES

Ted A. Jaske, Chicago, Ill.

Application June 24, 1944; Serial No. 541,928

1. Claim. (Cl. 7—14.5)

1.

This invention relates to thread cutters for thimbles and, while not restricted to any specific arrangement, it has particular reference to those arrangements in which the thimble forms part of or is associated with an outfit or sewing kit containing all the necessary accessories and parts for making repairs, such as spools with threads, needles and the like; these accessories are usually stored within a container which is closed by the thimble. The arrangement of a 10 thread cutter completes and improves the outfit rendering the use of cutting instruments such as scissors or knives unnecessary. It thus facilitates use of the outfit under circumstances in which normal accessories are not at hand.

The arrangement of a thread cutter, in order not to detract from the general usefulness of the thimble and especially from the usefulness of a sewing kit for repairs which has to be stored together with other objects in the pocket or pocket-book of the user, has however to fulfill certain special conditions. One of these conditions relates to the preservation of the general appearance, smooth outline and surface of the outfit, while another condition relates to the general arrangement of the cutter which has to be permanently fixed, and should form an efficient tool but should neither protrude nor permit accidental injury.

The present invention has the general object to meet the requirements which may arise under the circumstances set forth. The invention, therefore, consists in a thread cutter disk smaller in diameter than the small end of the conical thimble body, and permanently held within and enclosed by the said thimble body, an operative portion of which is rendered accessible through a single opening, cut or slot provided in the upper portion of the thimble. The end of the thread is introduced through this opening which is of sufficient width to provide insertion, but is sufficiently narrow to exclude the accidental introduction of objects or of any part of the human body, thus forming an efficient protection against any undesirable operativeness of the cutting edge. Preferably the cutter is located within the top portion of the thimble and is attached to or near the closing spherical cap portion of the same. It may be supported or held by an embossment at the inner side of the spherical cap either by rivet, screw or stud fixed to said cap portion, or between the latter and a spring inserted in a groove formed on the inner side of the conical portion below the cap portion.

The cutter consists of a circular disk which is rotatably arranged. Although only a small portion of said disk facing the hole, slot or cut is

2.

utilized during cutting, such an arrangement permits changing the operative part of the cutter, thus securing a long period of operativeness without renewal of the cutter.

Renewal of the cutter is however easily possible when the latter is fixed by suitable means such as a removable spring or spring disk.

Further objects, features and advantages of the invention will be apparent to those skilled in the art from the following detailed description of several modifications of the invention by means of which the cutter is clamped in the space below the top of the thimble.

Reference is now made to the accompanying drawings, in which:

Figure 1 is a view of an outfit or kit closed at the top by a thimble provided with a cutter.

Figure 2 is a similar view with the thimble removed from the container of the outfit and shown separately above the container.

Figure 3 is a cross-section through the kit.

Figure 4 is a plan view of the container.

Figure 5 is a cross-section similar to that of Figure 3 with the contents of the container removed, and showing a modification with a different method of affixing the thimble on the container for the accessories.

Figure 6 is a view of one modification of the thimble with the slot in front of the cutter.

Figure 7 is a plan view of the thimble looking toward the apex showing the cutter and the top portion.

Figure 8 is a cross-section taken along the line 8—8 of Figure 6.

Figure 9 is a similar cross-section through a modification of the thimble, in which the cutter is held by a spring.

Figure 10 is a plan view of this modification, while

Figure 11 shows, on an enlarged scale, the upper part of the thimble and the way in which the cutter is fixed by means of a spring.

The sewing kit or outfit shown in Figures 1 to 4 consists of a cylindrical or similarly shaped container 1 housing the sewing implements and accessories such as the spools 2, needles 3 and other accessories which form part of the kit. The cap of the container is formed by the thimble 4 which may be provided at its inside and near its lower edge with screw threads 5 engaging corresponding screw threads 6 provided on the outside of the container 1.

The thimble 4, a modification of which is shown in more detail in Figures 6 to 8, is of the usual type forming a single piece and comprises a conical portion 7 to be slipped over the finger of the person using the outfit, and a spherical segment

55

8 forming the cap of the thimble. Close to the spherical cap, so as not to reduce the space for the insertion of the finger, a cutter disk 9 is arranged, which may have any desired shape but preferably is a circular disk of a diameter smaller than the smallest diameter of the conical portion arranged near the line of intersection between the conical portion 7 of the thimble and the cap 8. The cutting disk is therefore confined to and contained within the inner contour of a normal conical thimble body, but is arranged close to the walls of the thimble so that by virtue of its position near the cap portion it cannot be reached accidentally by the finger inserted into the thimble and even if reached offers no opportunity for cutting, on account of its close fitting into the conical and spherical portion.

The disk 9 is arranged transversely with respect to the longitudinal axis of the thimble and it is mounted on a central embossment 10 or hub portion projecting centrally from the cap 8 and carrying a pin or bolt 11, which may either be riveted to the cap 8 as shown at 12 in Figures 3 and 5, or may be provided with a small screw 13, which permits removal of the cutter disk or a change of disks.

The thimble, in order to make the disk accessible is provided with an opening, cut or slot 14 which may have any desired shape: circular, elliptical, rectangular or the like, but which preferably has the shape of a longitudinal slot of such width that a thread may be easily passed through it while it is sufficiently narrow to prevent objects or parts of the human body to penetrate into the interior of the thimble, thereby protecting against accidental damage by the cutting edge of the cutter disk.

The latter may be a thin circular disk of steel, with a ground edge, similar to a razor blade which is preferably rotatably mounted on the hub portions of the cap.

Although the operative portion of the cutter disk is small, a circular cutting edge has the advantage of being able to change said operative portion at intervals in a very simple manner, thus keeping permanently a finely ground cutting edge in the operative position.

A small protuberance or stud 15 arranged on the disk permits rotation of the same if required.

To cut a thread (usually inserted into a needle) it is only necessary to pass the thread through slot 14 from the outside to the inside or if the end of the thread should be short, to move the thimble close to the spot where the cut has to be made and to pull the thread in such a direction that the cutting edge will be pressed against the thread.

Where cuts are not to be made close to the surface, insertion of the thread from either side may take place.

The cutter disk 9 is moved from time to time in order to make fresh portions of the cutting edge face the slot.

In the modification shown in Figure 5 the arrangement is substantially the same as that described, the fixation of the thimble on the container being however performed by means of a protruding annular ledge 11 on the container entering into a groove provided in the interior of the thimble.

According to the modification shown in Figures 9 to 11, the cutter disk is not fixed by means of a central pin but is merely held near the intersection between the conical portion 7 and the spherical cap 8 of the thimble or on an em-

bossment similar to that shown in Figures 3, 5, 6 and 8 by means of a spring 19 which may be inserted into grooves 20 provided in the interior of the thimble. The spring is of a suitable shape, for instance, it is circular or of U, V or W-shape, with parts protruding into the interior of the thimble and, when inserted and held within the groove by virtue of its elasticity, it will hold the cutter disk in close proximity to the cap. The cutter disk is thus confined to the space left between the spring 20 and the cap 8 and is held firmly but rotatably in this space. It may be rotated by means of the protuberance or stud 15 as shown in Figures 8 and 11 or by means of a small hole 21 provided on the disc.

It will be clear from the above that the invention may be used in connection with thimbles, whether or not attached to a kit or outfit. However, it will be understood that the fact that the smooth outline of the outfit is in no way impaired is a notable advantage. A further advantage resides in the fact that the operativeness of the thimble itself is not affected as is the case where cutting edges or the like are provided either on the edges of the cap or on the outside in general.

It is, however, clear that a number of changes may be made without departing from the scope of the invention and it is, therefore, emphasized that the foregoing specification is illustrative and is not intended to limit the scope of the invention as claimed.

Having described the invention, what is claimed as new is:

35 A thread cutter for thimbles, the latter having a body consisting of a single piece with a conical portion and a spherical segment forming its cap portion, and a flat circular disk of a diameter smaller than the smallest diameter of the conical body portion, having a circumferential cutting edge contained completely within the hollow interior of the thimble body, at the intersection between the conical and the spherical portion, the circumferential portion of said disk resting on and held by the said cap portion on one side, the conical portion of the thimble being provided near its small end with a groove located below the cutter disk, a spring seated within said groove, said spring holding said cutter disk rotatably, pressed against the cap portion, the thimble body being provided with a single narrow slot extending longitudinally of the wall of the thimble body and across said disk for making the cutting edge of the disk accessible from without.

55 TED A. JASKE.
